Primary Examiner—Bernard Ansher*Assistant Examiner*—Philip Hyder*Attorney, Agent, or Firm*—Trask, Britt & Rossa**[57] CLAIM**

The ornamental design for a treadmill base, as shown and described.

DESCRIPTION

FIG. 1 is a perspective view of a treadmill base showing my new design thereof;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of a handle assembly in FIGS. 1-7 is for illustrative purposes only and forms no part of the claimed design.
